CLAIM

The ornamental design for a LED fluorescent lamp, as shown and described.

DESCRIPTION

FIG. 1 is a front, left, and bottom perspective view of a LED fluorescent lamp, showing my design.

FIG. 2 is a right, rear, and top perspective view thereof.

FIG. 3 is a front elevation view thereof.

FIG. 4 is a rear elevation view thereof.

FIG. 5 is a top plan elevation view thereof.

FIG. 6 is a bottom plan elevation view thereof.

FIG. 7 is a left side view thereof.

FIG. 8 is a right side view thereof; and,

FIG. 9 is a partial enlarged view of an area labeled 9 in FIG. 1 comprising a connector and a fixing.

The evenly spaced broken lines immediately adjacent to the shaded areas depict the bounds of the claimed design, while all other evenly spaced broken lines are directed to environment. In addition, the dot-dash broken lines in the drawings illustrate an enlarged portion of the design. The broken lines form no part of the claimed design.
